ROTARY PUMP

Samuel Blaine Stine, Osceola Mills, Pa., assignor
to Kathryn R. Stine, Osceola Mills, Pa.

Application February 12, 1936, Serial No. 63,532

3 Claims. (Cl. 103—136)

My invention relates to rotary pumps and more particularly to pumps for pumping water or other liquids.

One object of my invention is to provide a 5 rotary pump with an improved and simplified shaft and vane assembly.

Another object of my invention is to provide in a rotary pump having radially movable vanes, means for so controlling the movement of the 10 vanes that a film or layer of grease can be formed and maintained on the inner walls of the pump chamber, to thereby protect the said walls against corrosion, and to serve as a primer.

Another object of my invention is to provide 15 a pump of the type referred to of such form that pressures therein will be relieved when the pump stops.

A further object of my invention is to provide a pump of the character referred to, having 20 vanes and guide means of such form that there will be less binding of the vanes than in various previously-known forms of pump.

One form which my invention may take is shown in the accompanying drawings wherein 25 Figure 1 is a plan view of the pump and a driving motor therefor; Fig. 2 is a side elevational view of the pump; Fig. 3 is a view taken on the line III—III of Fig. 1, on an enlarged scale; Fig. 4 is a view taken on the line IV—IV of Fig. 3; Fig. 5 is an edge view of one of the end plates of Fig. 3; Fig. 6 is a face view of the rotor; Fig. 7 is an end view thereof; Fig. 8 is a face view of one of the vanes, and Fig. 9 is an edge view thereof.

A base 10 serves as a support for a driving 30 motor 11, and a pump 12, the motor operating through a pinion 13, gear wheel 14, and a hollow shaft 15, to drive the impeller rotor of the pump.

The outer end of the shaft 15 is supported in 35 a bearing 16, and is provided with a grease cup 17 having a screw cap by means of which grease may be forced into the shaft. As shown more clearly in Figs. 3 and 4, the casing of the pump 12 comprises a peripheral wall 18 of generally 40 cylindrical form, having radially-extending flanges to which end plates 19 and 20 are secured by cap screws or bolts. The end plate 19 is provided with a hub-like extension 22, which forms a bearing for one end of the shaft 15. The 45 plate 20 has a hub-like extension 23 that surrounds the shaft and is provided with a packing gland 24. The packing gland has a notched flange with which a hinged retaining bar 25 cooperates to prevent accidental unscrewing movement of 50 the member 24. The cylindrical wall 18 of the

pump has an inlet opening 26, and a discharge opening 27.

A rotor 30 is welded or otherwise rigidly secured to the shaft 15, and is provided with radially-extending slots for propeller vanes 31. The 5 rotor and shaft are mounted eccentric to the axial center of the pump casing, so that the vanes 31 have limited radial movements in said slots, and are moved outwardly by centrifugal force, and said vanes at their outer edges, move 10 in proximity to the inner peripheral wall of the pump casing, so as to draw fluid through the pipe 26 and discharge it through the pipe 27. The end plates 19 and 20 are provided with annular ribs 32 and 33 respectively, with which stud-like 15 extensions 34 of the vanes 31 engage. The sides of the rotor are cored out, as clearly shown in Figs. 3 and 6, to receive the ribs 32 and 33 and also to reduce the area of surface contact between the vanes 31 and the slotted walls of the rotor, 20 thereby appreciably reducing friction. The position of the guide rings 32 and 33 with respect to the outermost edges of the vanes 31 is such that said edges are held out of actual engagement with the inner wall of the casing member 25 18, a distance of perhaps .007 inch. Thus a thinner walled casing may be employed, with less friction losses and it also reduces the rate of wear of the moving parts.

The vanes 31 may be of metal, but I prefer to 30 make them of molded non-metallic material such as phenolic condensation product, resin and fibrous compositions, etc., which give better wear and make less noise.

The axial length of each vane 31 near its outer 35 edge is greater than the over all axial length thereof at its inner edge including the stud portions 34. Thus, the ends of the studs 34 are not 40 permitted to engage the end plates 19 and 20, so as to cause tilting and binding of the blades in the rotor slots, since the ends of the blades or vanes near their outer edges will first engage the end plates. Also, the distance from the ends 45 of the studs 34 to the center of the blade is shorter than it would be if the studs were extended into grooves in the end plates 19 and 20. Thus, a lesser twisting force is imposed on the inner edges of the blades through engagement of the studs with the guide rings 32 and 33. The 50 studs 34 are preferably cylindrical in cross section and suitably hardened to reduce friction through engagement with the rings and to prevent excessive wear.

Radial clearance is provided at 55 between the

guide ribs 32 and 33 and the adjacent portions of the vanes 31, so that when the pump comes to rest with the parts in the position shown in Fig. 4, for example, the uppermost vane can drop 5 back slightly to leave a slight amount of clearance which will permit relieving of pressure or unloading of the pump at the upper side of the rotor, so that the pump can be more easily set in motion when pumping operations are to be 10 resumed. The innermost edges of the blades will, of course, have clearance, equal to the clearance at 36, with the adjacent portions of the rotor at 37 when the pump is operated. Force feed grease cups 38 and 39 are provided at the ends 15 of the pump casing, and are utilized to force grease into the pump chamber to prime the pump and to lubricate the shaft 15. Grease from the cup 17 will be forced from the shaft 15 through openings 40 in the rotor, at the base of each 20 vane 31. Clearance of perhaps .025 inch is provided between the ends of the rotor and vanes, and each end plate, so that the grease can be readily forced outwardly past the rotor into the pump chamber. 25

25. A heavy oil or fiber grease is employed which will be forced into contact with the inner periphery and end walls of the pump casing, so as to form an adherent film thereon which will harden through contact with cold water or the like, and thereby serve to protect the pump casing against corrosion and facilitate priming of the pump. This is of particular advantage when pumping acid mine water and the like. The thickness of the oil film will be approximately 30 equal to the clearance between the various parts 35 as above described.

The oil or grease need not necessarily be of the fibre grease type, but may be of various types which have a viscosity or consistency, designated 40 by the A. S. T. M. Penetrometer cone as penetration numbers 175 to 400.

It will be understood that when the pump reaches operating speed, the vanes will be under such centrifugal force that the circular bearing extensions 34 of the vanes will be moved 45 against the inner surfaces of the guide ribs 32 and 33, and the outer edges of the vanes will thereby be held in such spaced relation to the inner periphery of the pump casing that the grease film will be maintained that will protect 50 the pump chamber walls against corrosion and will serve as a "priming" when starting the pump.

I claim as my invention:—

1. A rotary pump comprising a rotor, a casing enclosing the rotor and having an inner peripheral wall disposed circumferentially of the rotor, impeller vanes carried by the rotor and movable radially thereof, under centrifugal and gravitational forces, guide means in the casing for so limiting outward movement of the vanes that their outer edges will be maintained in such spaced relation to the inner peripheral wall of 10 the casing that a heavy oil film can be maintained on said wall, and stop means limiting gravitational inward movement of the vanes when they are stopped in an upward position, there being such clearance between said stop means 15 and the vanes that when the vanes are in their retracted positions there will be substantial clearance between them and said oil film.

2. A rotary pump comprising a rotor, a casing enclosing the rotor and having an inner peripheral wall disposed circumferentially of the rotor, impeller vanes carried by the rotor and movable radially thereof under centrifugal and gravitational forces, means independent of the peripheral wall of the casing for limiting outward movement of the vanes, and means limiting gravitational inward movement of the vanes when they are stopped in an upward position, at such point that substantial clearance will be present between the outer edges of the vanes 25 and the inner peripheral wall of the casing.

3. A rotary pump comprising a rotor, a casing enclosing the rotor and having an inner peripheral wall disposed circumferentially of the rotor, impeller vanes carried by the rotor and 35 movable radially thereof under centrifugal and gravitational forces, axially extending studs carried by each vane at points adjacent to, but spaced inwardly from, inner edge portions of the vane, and annular guide ribs on the end 40 walls of the casing, extending into the adjacent spaces between said studs and the said inner edge portions, the said studs engaging the ribs to limit movement of the vanes under centrifugal forces, and there being sufficient clearance between the circumferential faces of the ribs and 45 said inner edge portions of the vanes to permit the vanes to move inwardly under the action of gravity, when in an upward position, such distance that there is substantial clearance between the outer edges of the vanes and the inner 50 peripheral wall of the casing.

SAMUEL BLAINE STINE.
